(57) **CLAIM**

The ornamental design for a packaging for beverage items, as shown and described.

DESCRIPTION

FIG. 1 is a front and side perspective view of a first embodiment of my packaging for beverage items;

FIG. 2 is front elevational view thereof;

FIG. 3 is a left side elevational view thereof, the right side being a mirror image thereof;

FIG. 4 is a rear elevational view thereof;

FIG. 5 is a top plan view thereof;

FIG. 6 is a bottom plan view thereof;

FIG. 7 is a bottom perspective view thereof;

FIG. 8 is a front and side perspective view of a second embodiment of my packaging for beverage items;

FIG. 9 is a front elevational view thereof;

FIG. 10 is a left side elevational view thereof, the right side being a mirror image thereof;

FIG. 11 is a rear elevational view thereof;

FIG. 12 is a top plan view thereof;

FIG. 13 is a bottom plan view thereof; and,

FIG. 14 is a bottom perspective view thereof.

The broken line showing of a packaging for beverage items represents unclaimed subject matter and forms no part of the claimed design.
